UNITED STATES PATENT OFFICE

2,462,082

THERMIONIC VALVE

John Foster, London, England, assignor, by mesne assignments, to International Standard Electric Corporation, New York, N. Y., a corporation of Delaware

Application October 28, 1942, Serial No. 463,701
In Great Britain December 19, 1941

8 Claims. (Cl. 250—27.5)

1

The present invention relates to electron discharge devices for use at ultra high frequencies of the kind in which the electron stream is density modulated by controlling the flow of electrons from the cathode and the density modulated beam is employed to excite a hollow resonator from which the output is obtained.

Such devices of the type specified have many advantages over other known electron discharge devices for use at ultra high frequencies, such as those working on the electron velocity modulation principle or electron deflection principle. In particular the noise level in devices in which the electron flow is controlled is much lower than in the other types.

In order to adapt the well known grid controlled electron flow multielectrode valve comprising a cathode, anode and control grid for use at ultra high frequencies, it is necessary to eliminate troubles due firstly to electron transit time effects, and secondly to the coupling between the input and output circuits in the form of inter-electrode capacities, and self- and mutual-inductances of the leads.

The troubles due to the coupling between the input and output circuits have been overcome in the kind of device to which this invention relates by using the density modulated beam to excite a resonant chamber from which the output is taken. Such a device operates efficiently as a wide frequency-band amplifier, and has a low noise characteristic as opposed to beam velocity and deflection controlled devices.

It is the object of this invention to provide an improved device of the kind hereinbefore specified of simpler construction than known devices of that kind.

According to the invention such a device comprises a cathode, a control grid and an anode or collecting electrode, a U-shaped metallic member containing said cathode and control grid parallel to the base thereof, a pair of metallic plates spaced in the direction of electron flow from the limbs of said U-shaped member to form a first gap between said plates and limbs and spaced from the anode or collecting electrode to form a second gap between said plates and anode and a metallic disc sealed into the wall of the device and having an aperture therein to allow of the passage of the electron stream therethrough and adapted to form a part of a hollow resonator arranged to be inductively excited by the passage of the electron stream across the said second gap.

The invention will be further described by way of example as embodied in the electron discharge

2

device illustrated in the accompanying drawings, in which Figures 1, 2 and 3 are plan, side and end views respectively, with the glass envelope of the device shown in section, as well as the outer wall of the resonator in Fig. 1, Figure 14 shows a detail in section.

Referring to the drawings, the electron discharge device comprises an electrode assembly which consists of a cathode 1, control grid 2 and second grid 3. The cathode is connected to a U-shaped electrode 4 whose base is constructed to form a condenser, with a plate 27 as herein-after described in connection with Fig. 4. The grid 3 is connected to this condenser by a very short lead 15 of low self inductance. This almost eliminates any tendency to instability. The leads 5 and 5a are connected to the control grid 2 by means of a short conductor 29 and the leads 6 and 6a are connected to the cathode by means of conductor 22. These leads form a comparatively low loss path for the introduction of the signal. The input circuit between 5 and 6 or 5a and 6a could conveniently be a screened Lecher system. The cathode heater current leads 7 and 8 are passed through the press 16 in well-known manner as well as the D. C. voltage lead 9 for grid 3.

One side only of the cathode 1 is coated with electron emissive material and the electrons after passing through grid 3 are formed into a narrow beam indicated at 17 by the electron lens formed by the gap 18 between shields 19 and U-shaped electrode 4. This beam passes through an aperture 12 in a copper disc 11 sealed in the glass envelope and impinges on the anode 13.

The electrodes 4 and 10 are mounted on rods or wire bars which are supported in two parallel mica plates 19 and 20. Springs 21 are mounted on and in direct electrical contact with two of the said bars, and when the electrode assembly is placed in position the springs press against the disc 11 and so make good electrical connection between the disc 11 and the shield electrodes 10.

The condenser incorporated in the base of the U-shaped electrode 4 is shown more clearly in Figure 4 and comprises a metal plate 27 sandwiched between two sheets of mica, as shown in the drawing. These three elements are then sandwiched between the bottom of the U-shaped electrode and a channel shaped member 21 the ends of which are soldered or welded to the limbs of the electrode 4. The centre plate 27 of the condenser is provided with a tab at each end thereof. In Fig. 4, only one tab 24 is visible, the position of the other tab 25 being shown in the drawing. One of these tabs, namely 25

is connected to the grid 3 by the short lead 15, as already stated and the other tab 24 is connected to the lead 9 which is brought out through the press 16 and enables a positive potential to be applied to the grid 3. The other plate of the condenser formed by the base of the electrode 4 and member 21' is connected to the cathode by means of a connector 22.

The ends of the electrodes 10 are brought in close proximity to each other and are provided with parallel portions 23 which pass through the aperture 12 in the disc 11 and enable the input structure to be aligned with the aperture 12. The length of these portions 23 may be such as to leave a gap between these members and the anode 13 of the order of .100 inch.

In use a high-Q coaxial resonator 26 (Fig. 1) is placed on the anode 13 and disc 11 or other resonant chamber may be mounted on the disc 11 to present a high impedance to the beam.

When an ultra-high-frequency signal is fed into the grid 2 the beam becomes space-charge-density modulated and thus excites inductively the output resonator as it passes from the aperture 12 to the anode 13. As this time is short the output efficiency is very nearly 100%. The transit time of the electrons from cathode to anode introduces a phase change between the input and output voltages, but is otherwise of no importance. The use of reasonably high voltages enables the distance from the anode 13 to the aperture 12 to be quite large thus reducing the output capacity to a low value.

The voltages applied to the control grid may be of the order of -1.5 volts, to the grid 3 of the order of 150 volts, to the disc 11, shield electrode 10 and anode 13 of the order of 700 volts, and the U-shaped electrode 4 at zero volts or cathode potential.

In one practical case

Input capacity-----	6.0	μuf.
Output capacity-----	0.5	
Feedback capacity-----	<.0005	

The emission current was 8.0 ma., and was controlled by the potential on the control grid giving a slope of the characteristic curve of 6.5 ma./v.

Gain at 600 megacycles per second with 4 megacycles per second band width=28 decibels.

The advantage of the electron discharge device according to the invention for amplification of ultra high frequencies are:

(1) Elimination of input damping due to cathode lead inductance.

(2) Elimination of instability, the accelerating grid 3 to cathode decoupling condenser (contained within the base of the U-shaped electrode 4) being connected to these electrodes by short leads of low inductance.

(3) Low output capacity enabling use of a high Q resonator, thereby increasing the gain and increasing the frequency band width.

(4) Elimination of instability due to anode-grid capacity, this being reduced to a negligible quantity.

(5) The low noise characteristic of space-charge controlled devices as opposed to velocity and deflection controlled devices.

What is claimed is:

1. An electron discharge device for use at ultra high frequencies comprising a cathode, a control grid, and an anode, a U-shaped metallic member having flat parallel limbs containing said cathode

and grid spaced from the base thereof, a pair of metallic plates substantially in the planes of said limbs and spaced in the direction of electron flow from said limbs forming a first gap between said plates and limbs and spaced from said anode forming a second gap between said plates and anode, and a metallic disc sealed into the wall of the device and forming part of a hollow resonator, said disc being positioned between said first and second gaps and having an aperture therein to allow of the passage of the electron stream therethrough.

2. An electron discharge device according to claim 1 wherein the ends of said plates near the anode are brought into close proximity to each other and are provided with parallel portions which pass through the aperture in the said metallic disc.

3. An electron discharge device according to claim 1 further comprising means for making separable direct electrical contact between said plates and disc, said means being supported on one of said last mentioned elements and adapted to engage the other.

4. An electron discharge device according to claim 1 further comprising spring members secured to metallic supporting bars for said plates and adapted to press against said metallic disc for making the electrical connection therewith.

5. An electron discharge device according to claim 1 further comprising straight parallel wires which pass through the envelope of the device and are connected with the cathode and control grid, respectively, to form a low loss path for the input of the device.

6. An electron discharge device according to claim 1 further comprising an accelerating electrode and a decoupling condenser connected between said accelerating electrode and cathode, said decoupling condenser being incorporated in the base of said U-shaped member and connected directly to said accelerating electrode and cathode.

7. An electron discharge device according to claim 1 comprising a connection between said cathode and said U-shaped member.

8. An electron discharge device according to claim 1 further comprising an accelerating electrode and the base of said U-shaped member comprising a double wall, a decoupling condenser comprising a metallic sheet sandwiched between two mica sheets contained within said double wall, said sheet having two tabs, one connected by a short lead to said accelerating electrode and the other connected to a lead passing through the envelope of the device.

JOHN FOSTER.
